CONVERSION OF HYDROCARBON OIL

James W. Gray, Summit, N. J., assignor to Gasoline Products Company, Inc., Newark, N. J., a corporation of Delaware

Application July 23, 1936, Serial No. 92,067

2 Claims. (Cl. 196—58)

This invention relates to the conversion of high boiling hydrocarbon oil into lower boiling hydrocarbons suitable for motor fuel and pertains more particularly to the processing of heavy oil such as reduced crude, heavy gas oil or an oil containing crude residual constituents.

It has heretofore been a practice to subject heavy oil stocks such as reduced crude, heavy gas oil or other oil stocks having coke-forming tendencies to mild cracking treatment, commonly known as viscosity breaking treatment, controlled to produce a maximum yield of gas oil suitable for high temperature drastic cracking treatment. In some instances the temperature necessary to effect the mild cracking treatment of the heavy oil has been accomplished by passing the oil through a separate heating coil located within a furnace, and in other cases the heavy oil has been heated to the required mild cracking temperature 20 by direct contact with more highly heated products, such as products from a high temperature cracking operation.

My invention is directed to an improvement in a process of the general type last mentioned 25 wherein the mild cracking of the heavy oil is accomplished by direct contact with highly heated products from a cracking operation.

The principal object of my invention is to accomplish the mild cracking treatment of the 30 heavy oil in a more simple and effective manner.

A further important object of my invention is to effect the mild cracking or viscosity breaking treatment of the heavy oil in a lesser amount of equipment.

35 A further important object of my invention is to obtain a greater degree of mild cracking or viscosity-breaking treatment of heavy oil charged to the system while minimizing coking.

More specific objects and advantages of my 40 invention will be apparent from the more detailed description hereinafter.

In accordance with my invention, highly heated products from a high temperature cracking operation, processing clean condensate stock, are injected into an enlarged zone containing a body of heavy oil, such as reduced crude, in such manner as to rapidly and effectively separate the cracked vapors from the cracked residue so that the cracked vapors pass directly in contact with 50 the heavy oil undergoing viscosity breaking treatment, while the unvaporized residue is rapidly separated and withdrawn from the enlarged zone without being subjected to extended cracking in the enlarged zone.

55 For a better understanding of my invention

reference is now made to the accompanying drawing which is a diagrammatic illustration of an apparatus, having parts shown in section, suitable for carrying the invention into effect.

Referring to the drawing, the numeral 10 designates a charging line through which a clean condensate stock, amenable to high temperature drastic cracking treatment, is forced by means of pump 11 to the heating coil 12. This clean condensate stock may comprise condensate resulting from fractionation of the cracked vapors in fractionating tower 13, in which case the condensate is withdrawn from the bottom of the tower 13 through line 14 which merges with charge line 10, or the charging stock to heating coil 12 may consist in whole or in part of clean condensate oil from an extraneous source, in which case the extraneous oil is introduced into the system through line 15 forming an extension of line 10.

The clean condensate charge during its passage through the heating coil 12, located in the radiant heat section of the furnace 16, provided with burners 17, is rapidly heated to a high cracking temperature such as from 950° to 1050° F. 25 or thereabouts.

The oil, after being heated to the desired cracking temperature of the order mentioned, is allowed to remain at the high temperature for a period sufficient to effect the desired conversion. 30 To this end the oil may be caused to pass through tube bank 18 located in the convection section of the furnace. In some cases it may be desirable to complete the conversion in an enlarged digestion chamber in which event the oil from the furnace passes via lines 18 and 19 to a reaction chamber 21 wherein the desired conversion is carried to completion.

The cracked products, after undergoing the desired conversion within the furnace 16, or after 40 being completed in reaction chamber 21, in event the latter is employed, are passed through transfer line 22 through a tangential inlet 26 to the bottom section of a separator and cracking chamber 23 directly below a baffle plate 24 which is of 45 the doughnut type, having a central opening 25. While I have shown the inlet pipe 26 as being preferably tangential, this pipe may be pointed partially downwardly, or upwardly, or if desired, against the side wall of the chamber 23.

The cracked products from the transfer line 22, entering the bottom section of the separator 23 preferably in a tangential direction, cause a rapid whirling of the products in the bottom of the separator 23 below the baffle 24, thus effecting 55

a rapid separation of the vapors from the cracked residue and forcing the vapors toward the center of the chamber where they pass upwardly through the opening 25 in the baffle 24, while the heavier cracked residue is forced outwardly against the wall of the chamber where it drops to the bottom of the separator and is removed therefrom through line 27 before the cracked residue is permitted to undergo extended cracking within the 10 separator 23.

The cracked vapors liberated in the bottom section of the separator pass upwardly through the chamber in direct countercurrent contact with a relatively heavy oil, such as crude, reduced crude, 15 heavy gas oil or other oil stocks. This heavy oil, which may be preheated to a temperature of about 500° F. or higher or which may be used at atmospheric temperature is introduced into the chamber 23 through a charge line 28 provided 20 with a pump 29. The heavy oil, upon contacting with the hot cracked vapors, is heated to a mild cracking temperature, such as from 700° F. to 810° F. or preferably 730° to 780° F. and is maintained within the chamber for a period sufficient 25 to effect a substantial amount of cracking to form a maximum yield of intermediate cycle stock suitable for high temperature cracking essential to the production of maximum yields of high anti-knock gasoline. For example, the 30 heavy oil may be cracked within separator and cracking chamber 23 to convert from 15 to 30 per cent into constituents below the initial boiling point of the original charge of which from 8 to 15 per cent may be within the gasoline boiling 35 range.

The unvaporized portion of the heavy oil charged to the chamber 23 through line 28, after being subjected to the desired cracking treatment in the upper section of the separator and cracking 40 chamber 23, with moderate rapidity passes through opening 25 in baffle 24 and merges with the cracked products from line 26 and is rapidly heated to the higher temperature prevailing below the baffle 24 to effect vaporization of clean 45 heavy gas oil contained in the unvaporized portion for retreatment in the upper part of the chamber 23 above the baffle 24.

In practicing my invention, a temperature differential is maintained on the oil in the spaces 50 below and above the baffle 24. It is essential to maintain a higher temperature below the baffle 24 than above it, this temperature differential generally being between 10° and 100° F. and in most instances between about 30° and 70° F. As 55 a result of the higher temperature prevailing in the space below the baffle 24, heavy gas oil contained in the unvaporized portion of the heavy oil descending into this space from above the baffle 24 is vaporized therefrom and passes upwardly wherein it is further cracked and soaked. In operating with a temperature differential in the spaces below and above the baffle 24, a marked 60 difference in gravity of the oils in these spaces has been found to exist. For example, the heavy oil in the space below the baffle 24 has been found to have a gravity of from 2° to 8° A. P. I. heavier than the oil above the baffle and generally 65 between 4° and 6° A. P. I. heavier.

The size of the opening 25 determines the temperature differential in the spaces below and 70 above the baffle 24. This size may be varied manually before operation is begun, or during operation the same effect may be accomplished by bleeding part of the oil from the space above 75 the baffle 24, such as through part of the line 31

and line 31' to the space below the baffle 24. If the size of the opening 25 is too large, it is difficult to maintain the desired temperature differential. The size of the opening should be varied depending upon the conditions of operation and the 5 size of equipment. As an example, with a tower, such as 23, nine feet in diameter, and with 250 bbls. of oil per hour at 1025° F. entering it through the tangential entry 26, it was found desirable to have an opening 30 inches in diameter. 10

A substantial body of heavy oil is maintained within the separator and cracking chamber 23. This may be accomplished by maintaining a relatively high liquid level within the chamber, as shown, or the heavy oil may be caused to cascade 15 over suitable baffles 23' against the upwardly flowing stream of vapors.

In some cases it may be desirable not to complete the mild cracking of the heavy oil in chamber 23, in which event, according to a further 20 phase of my invention a portion of the unvaporized heavy oil is withdrawn from chamber 23 directly above the baffle 24 through line 31 and forced by means of pump 32 either to the tubular bank 17 in the convection section of furnace 16 25 30 or a part of the unvaporized heavy oil may be introduced into the transfer line 19 leading to the reaction chamber 21 in event the latter is employed. Or if desired, a part of the unvaporized oil may be introduced in line 22 on either side of valve 41. When part of the unvaporized oil is withdrawn through line 31, it is generally desirable to provide an extension 30 35 on baffle 24 to prevent vapors from being withdrawn with liquid oil.

Vapors formed within the separator and cracking chamber 23 commingled with cracked vapors liberated therein and remaining uncondensed pass overhead through line 33 to the fractionating 40 tower 13 wherein they are subjected to fractionation and rectification to condense insufficiently cracked products as reflux condensate. To this end the top of the fractionating tower is provided with a suitable trimming coil to regulate the 45 exit temperature of the vapors. If desired, additional reflux, such as final distillate, may be introduced directly into the top of the tower in lieu of or supplemental to the trimming coil 34.

Fractionating tower 13 is provided with conventional fractionating elements, such as bubble 50 trays, to effect the desired rectification of the vapors.

Vapors remaining uncondensed in tower 13, which include the sufficiently converted constituents, pass overhead therefrom through line 35, 55 provided with a condenser 36, wherein the desired distillate condenses, to a receiving vessel 37 where the desired distillate separates from fixed gases.

Fixed gases are withdrawn from receiving vessel 37 through line 38 and passed to a gas recovery plant, not shown, and the final distillate is withdrawn from the receiving vessel through line 39. The desired pressure may be maintained on the coils 12 and 17 and the reaction chamber 21, if 60 used, by means of valve 41.

The pressure maintained on the equipment is not considered critical and may vary over a relatively wide range. The pressure may be maintained substantially uniform throughout the 70 equipment except for the necessary differential to effect the desired flow, or a substantial pressure drop may be employed between the heating coil outlet and the separating and cracking chamber 23. In the latter event the transfer line 75

22 is provided with a pressure-reducing valve 41. The outlet of the heating coil or the outlet of the reaction chamber 21, in event the latter is used, may be maintained under a pressure ranging 5 from 400 to 800 or more pounds per square inch, whereas the pressure in the separator 23 and fractionating tower 13 may range from atmospheric to about 400 pounds per square inch.

The following example will serve as a guide in 10 carrying out my invention to obtain the greatest benefits therefrom, it being understood that the values given are illustrative rather than limitative.

Charging stock for the cracking coil consisting 15 of clean cycle stock from the fractionator is heated to a temperature of from 900° F. to 1050° F. during passage through the furnace 16 and maintained at cracking temperature for a period adequate to convert from 20 to 40 per cent into constituents within the gasoline boiling range during 20 each pass through the furnace. The outlet of the pressure of the coil may be maintained between 100 and 800 pounds per square inch. The pressure within the separator 23 may be reduced 25 to from 50 to 100 pounds per square inch. Reduced crude is introduced into the separator 23 at a rate such that the ratio of fresh charge to cracked vapors is such as to raise the temperature of the heavy oil above the baffle 24 to from about 30 730° F. to 780° F. with the temperature below the baffle 24 being from about 780° F. to 825° F. The fresh oil is maintained within the separator under cracking conditions for a period sufficient to accomplish the desired conversion.

35 Having described the preferred embodiment of my invention, it is understood that it embraces such other modifications and variations as come within the scope thereof, and it will be further understood that it is not my intention to dedicate 40 any novel features or unnecessarily limit my invention except as necessary to distinguish from prior art.

I claim:

1. A method for processing hydrocarbon oil to produce lower-boiling hydrocarbons suitable for motor fuel which comprises subjecting a condensate oil to cracking conditions of temperature and pressure to effect extensive conversion into gasoline hydrocarbons, introducing the resultant 45 cracked products, comprising vaporous and residual products of reaction, at cracking temperature into a confined zone below a baffle in the lower portion of a reaction chamber in a stream tangential of the chamber so as to thereby establish and maintain in said confined zone a whirling mass of products promoting a rapid separation of residual products from vapors and gases which collect about the axis of the whirling mass, withdrawing liquid residual products from the lower portion of said confined zone, withdrawing the vapors and gases so collecting from said confined zone by passing them through a central opening in said baffle and thence upwardly into a body of liquid oil maintained in the reaction chamber above said 50 baffle while retaining the liquid whirling mass below said baffle, introducing into the upper portion of said reaction chamber and substantially above said baffle a hydrocarbon oil heavier than said clean condensate oil whereby said heavier oil passes downwardly through said upper portion of said chamber in countercurrent contact to said ascending hot gases and vapors, regulating the ratio of said heavier oil to said hot gases and vapors and maintaining contact thereof for a 55 time sufficient to effect cracking of said heavier oil in said upper portion of said chamber whereby vaporous and gaseous products of such cracking separate from unvaporized oil and pass upwardly with said hot gases and vapors, permitting residual oil from said body of oil undergoing cracking to pass downwardly through said central opening in said baffle and into admixture with the whirling mass below the baffle whereby said residual oil is quickly raised to a higher temperature to 60 effect further cracking and vaporization thereof, withdrawing residual oil from said body of oil above said baffle and introducing the oil so withdrawn, without passage through said confined zone, into an intermediate point in said 65 passageway of restricted cross section to thereby admix it with the stream undergoing cracking therein and effect a further conversion of the introduced oil.

JAMES W. GRAY. 70

current contact to said ascending hot gases and vapors, regulating the ratio of said heavier oil to said hot gases and vapors and maintaining contact thereof for a time sufficient to effect cracking of said heavier oil in said upper portion 5 of said chamber whereby vaporous and gaseous products of such cracking separate from unvaporized oil and pass upwardly with said hot gases and vapors, permitting residual oil from said body of oil undergoing cracking to pass downwardly through said central opening in said baffle and into admixture with the whirling mass below the baffle whereby said residual oil is quickly raised to a higher temperature to effect further cracking and vaporization thereof, and fractionating vapors from said reaction chamber to separate a desired distillate product.

2. A method for processing hydrocarbon oil to produce lower-boiling hydrocarbons suitable for motor fuel which comprises passing a condensate oil through a passageway of restricted cross section in which the oil is heated to a cracking temperature under superatmospheric pressure to effect extensive conversion into gasoline hydrocarbons, introducing the resultant cracked 25 products, comprising vaporous and residual products of reaction, at cracking temperature into a confined zone below a baffle in the lower portion of a reaction chamber in a stream tangential of the chamber so as to thereby establish and maintain in said confined zone a whirling mass of products promoting a rapid separation of residual products from vapors and gases which collect about the axis of the whirling mass, withdrawing liquid residual products from the lower portion 30 of said confined zone, withdrawing the vapors and gases so collecting from said confined zone by passing them through a central opening in said baffle and thence upwardly into a body of liquid oil maintained in the reaction chamber above said 35 baffle while retaining the liquid whirling mass below said baffle, introducing into the upper portion of said reaction chamber and substantially above said baffle a hydrocarbon oil heavier than said clean condensate oil whereby said heavier oil passes downwardly through said upper portion of said chamber in countercurrent contact to said ascending hot gases and vapors, regulating the ratio of said heavier oil to said hot gases and vapors and maintaining contact thereof for a 40 time sufficient to effect cracking of said heavier oil in said upper portion of said chamber whereby vaporous and gaseous products of such cracking separate from unvaporized oil and pass upwardly with said hot gases and vapors, permitting residual oil from said body of oil undergoing cracking to pass downwardly through said central opening in said baffle and into admixture with the whirling mass below the baffle whereby said residual oil is quickly raised to a higher temperature to 45 effect further cracking and vaporization thereof, withdrawing residual oil from said body of oil above said baffle and introducing the oil so withdrawn, without passage through said confined zone, into an intermediate point in said 50 passageway of restricted cross section to thereby admix it with the stream undergoing cracking therein and effect a further conversion of the introduced oil.
